UNITED STATES PATENT OFFICE.

HUGO KARL GRÜNDIG, OF DRESDEN, GERMANY.

SHELL FOR INDUCTIVE HIGH-TENSION APPARATUS CONSISTING OF ANNULAR INSULATING MEMBERS.

Application filed July 6, 1925. Serial No. 41,854.

To all whom it may concern:

Be it known that I, HUGO KARL GRÜNDIG, a citizen of Germany, residing at Dresden, in Saxony, Germany, have invented certain new and useful Improvements in Shells for Inductive High-Tension Apparatus Consisting of Annular Insulating Members, of which the following is a specification.

The present invention relates to improvements in shells for inductive high tension apparatus consisting of annular insulating members placed on top of each other so as to form a column. It is already known to construct the shells of inductive high tension apparatus such as transformers and choking coils, for example, consisting of several inductive member systems of different potential step, of an equal number of annular insulating bodies containing one member system each in such a way as to form a column. According to the present invention this type of construction is modified and improved so as to cause the frame-like horizontally arranged cores of the member systems to be held in position and surrounded by two successive shell members at their joints. These shell members are placed on top of each other and firmly and tightly connected with each other across the joints in a manner, which will be described later on. This arrangement results in the production of an oil-tight and particularly simple structure in so far as no special supports are required which, with respect to insulation and static field effect, may possibly need special treatment, while the arrangement of the cores between the shell members forms a counter-influence in regard to electro-dynamic forces. Furthermore, the horizontal position of the cores and their arrangement and connection according to the present invention will permit an extremely low type of structure as compared with the total potential drop.

The type of construction outlined above uses as shell members hollow bodies of insulating material, which, in the known manner, are provided with a passage for the reception of the connecting piece of the core and the inner winding. For the purpose of this invention the hollow bodies consist of a wider upper and a narrower lower part, so that the latter will fit into the upper part of

the adjacent shell member arranged below, while the wider upper parts produce the 55 wall of the column. The top of the column may be formed by a hollow body having a passage of known shape. The mode of construction disclosed here is distinguished by special safety and protection against short-circuit, so as to permit a still further reduction of the dimensions of the whole apparatus.

The lowest member or base of the column may consist of a hollow iron body anchored 65 to the ground. Inside this hollow body rests the core of the lowest member system on an annular support, while the outer wall of the hollow body ends in a round flange or rim, surrounds and envelops the 70 lower edge of the first insulating shell member and is cemented to it.

The device forming the subject of this invention is chiefly to be used as high tension transformer, and several modifications of it 75 are shown in the accompanying drawings.

Fig. 1 is a longitudinal section; Fig. 2 an elevation; Fig. 3 a cross-section of a high tension transformer; Figs. 4-7 longitudinal sections of different modifications of 80 the connection between the members of the column; Fig. 8 a modification partly in section of a structure shown in Fig. 1; Fig. 9 a partial elevation thereof; Fig. 10 a horizontal section thereof; Fig. 11 a vertical 85 section of another modification of the structure shown in Fig. 1; Fig. 12 a partial elevation thereof and Fig. 13 a cross-section thereof.

Referring first to the structure shown in 90 Figs. 1-3, a' , a^2 , a^3 and a^4 denote annular insulating members and 2 the cores arranged in the spaces between two superposed members and which consist of a frame with connecting piece, in the joints between each two 95 successive members. Member a' is a plain annular section inserted in the outer base 3, while the other members are provided with sleeve-like extending projections 9, which overlap the cores 2 and the edges of the annular members below and which are cemented with the said edges at 10, when in a condition of axial pressure. The edge of the base 3 is also cemented at 12 with the 100 sleeve-like projection of the annular member a^3 . The top annular member a^4 is of 105

2 dome-like shape and carries the bell 11. The connecting pieces of the cores are enveloped by the insulating coil pieces 5 and support within these coil pieces the secondary windings 6, while the coil pieces themselves carry the primary windings 7. To the upper edges of the annular members, in a downward direction, are connected the Faraday cages 8, which consist of two pieces 10 and which serve at the same time for conducting the current to the next member. The secondary poles are laterally extended from the last lowest member. The supply of current to the top primary winding 7 is shown in Fig. 1. The inside of the column is 15 filled with oil close to the upper edge.

Figs. 4-7 show several modifications of connection of the members of the column, and Figs. 6 and 7 indicate sleeve-like projections 9 overlapping the edge of the neighboring member in a manner similar to that shown in Fig. 1. In Figs. 6 and 7, however, the edges of the neighboring annular members almost meet, while the core 25 2 lies between inner flange-like projections 13 of the walls. In Fig. 5 the core is similarly held, while the sleeve-like projection has been omitted and connection is established by a hollow metal ring 15 overlapping 30 the joint. A similar hollow ring is shown in Fig. 4 too, but horizontally divided and of flange-like shape, so as to facilitate the disassembling of the members.

A modification in which the annular members are integral with a passage instead of being provided with specially inserted coil members 5 is illustrated by Figs. 8-10. Having a square basic form each shell member, in the horizontal section of the core, 40 has the structure shown in Fig. 10, viz., the shell member has a pipe-like passage 14 connecting two opposite walls, the said passage receiving the connecting piece of the core 2 and the secondary coil 6 and carrying on 45 its outside the primary coil 7. The core plates, however, are in this modification also held and pressed together between two horizontal reductions of successive shell members. These shell members are connected, 50 according to Fig. 5, by means of sleeves which, for electrical reasons, have the form of hollow rings 15 of rounded section and which are cemented with the two successive shell parts. This manner of connection 55 produces the greatest strength with respect to short-circuit strains and permits disassembling of the shell without damaging the porcelain bodies. The core of the lowest member in this modification may be carried in 60 any manner desired as, for example, by a hollow body 16. The top part of the shell is contracted and covered with a cap 11 to which are attached the terminals for primary connection. The members are here 65 also connected by divided Faraday cages 8.

Special mention must be made of the form of the center members in so far as they rest on each other with their wider upper parts, while their narrower lower parts engage the nearest lower member.

Figs. 11-13 represent a modification, which, with respect to the form of the shell members having a passage, conforms with the last described structure, and which, in regard to the mutual connection of the shell members, is similar to the structure shown in Figs. 1-3.

What I claim is:

1. In an inductive high tension apparatus, particularly a high tension transformer, consisting of several inductive units of different potential, a column-like shell composed of several superposed annular insulating members and in which the transversely extending cores of the different units are arranged between the edges of two adjacent shell members.

2. In an inductive high tension apparatus, particularly a high tension transformer, consisting of several inductive units of different potential, a column-like shell composed of several superposed annular insulating members in which the transversely extending cores are arranged between the edges of two adjacent shell members and hollow rings overlapping the joints of each two adjacent shell members and cemented to both said members.

3. In an inductive high tension apparatus, particularly a high tension transformer, consisting of several units of different potential, a column-like shell composed of several superposed annular insulating members between the edges of which are arranged transversely the cores of said units, and hollow rings overlapping the joints of adjacent shell members and cemented to the latter, said hollow rings being divided across the joints and formed with flanges to facilitate the disassembling of said members.

4. In an inductive high tension apparatus, particularly a high tension transformer, consisting of several units of different potential, a column-like shell composed of several superposed annular insulating members between the edges of which are arranged transversely the cores of said units, said shell members being formed as hollow bodies, each having a passage for the reception of the connecting piece of the core and inner winding and a wider upper and lower narrower part, the narrower lower part being adapted to fit in the upper wider part of the adjacent hollow body and said wider upper parts constituting the wall of the column.

5. In an inductive high tension apparatus, particularly a high tension transformer, consisting of several inductive units of different potential, a column-like shell com-

posed of superposed annular insulating members between the edges of which are arranged transversely the cores of said units, a hollow iron body constituting the base of the column and adapted to be anchored to the ground and to carry the core of the lowermost shell member by means of a ring, the outer wall of said hollow body terminating in a rounded edge overlapping the lower edge of the adjacent shell member and cemented thereto.

In testimony whereof I affix my signature.

HUGO KARL GRÜNDIG.
